United States Patent Office

Des. 191,488
Patented Oct. 3, 1961

191,488

BRUSH

Samuel J. Golden, 2095 Grand Concourse, 180th St.,
Bronx, N.Y.

Filed Mar. 30, 1961, Ser. No. 64,558

Term of patent 14 years

(Cl. D86—10)

FIG. 1 is a top plan view of the brush, showing my new design.

FIG. 2 is a front elevational view of FIG. 1.

FIG. 3 is a back elevational view showing the opposite side of FIG. 2.

FIG. 4 is an end elevational view.

I claim:

The ornamental design for a brush, as shown.
